LOCKING CONTROL CIRCUIT FOR FLUID-ACTUATED MOTORS

Warren R. Tucker, Mount Gilead, Ohio, assignor
to H-P-M Development Corporation, Mount
Gilead, Ohio, a corporation of Delaware

Application November 7, 1949, Serial No. 125,877

1 Claim. (Cl. 60—52)

1

The present invention relates generally to control circuits for fluid-actuated motors or reciprocating rams. More particularly, the present invention deals with an improved hydraulic circuit for hydraulic motors or rams of the type used to impart reciprocating or oscillatory movement to a member or members of various types of machinery. In its more specific aspects, the present invention is concerned with a hydraulic control circuit for use in connection with a hydraulic motor or ram which is employed as an actuating member for the clamping arms or grapples of a loader or lifting mechanism, although it will be understood that the present improved control circuit may be employed in connection with any type of reciprocating hydraulic motor wherein it is desirable to lock the reciprocating member of the motor in a given position of extension or retraction with respect to the ram and prevent the slippage or creeping of the reciprocating member after movement thereof to a said desired position.

In the past, fluid-actuated hydraulic motors or rams have been employed with facility in replacement of various types of mechanical movements in machinery, and for some time, it has been proposed to employ such hydraulic motors or rams as a means for actuating the clamping or grapple members of portable lifting and elevating machines or vehicles. However, the use of hydraulic motors in this capacity has been limited due to the tendency of the reciprocating member of the motor or ram to slip or creep after being initially actuated to a load-clamping position, thereby allowing the load to be dropped or released inadvertently.

In most instances, where hydraulic rams or motors are employed, the motor is under control of a multiple way hydraulic control valve which functions to direct fluid under pressure of a suitable pump into the pressure area or areas of the motor to actuate the movable plunger of the motor. Also, such control valves are usually operable to create a partial lock within the fluid motor or ram while at the same time directing the pump discharge to exhaust, in order that free circulation of the pump is obtained when the movable member of the motor is maintained in a stationary position.

However, in most instances, the multiple way control valves employed in directing fluid to the various pressure stages of the hydraulic motor do not function to provide an efficient lock within the motor when conditioned to a neutral or pump by-passing position. Generally, such multiple way control valves embody a movable spool

element which serves to alternately establish communication between the various ports or outlets of the valve and to interrupt communication between other of the ports of the valve. Due to the necessity for freedom of movement of the valve member of such control valves and the relatively loose fit between the valve chamber and the movable valve member inherent to such valves, it is impracticable, if not impossible, to obtain an absolute lock of the hydraulic fluid within an associated motor under the control of such valves, depending upon the control valve alone as a means for establishing a lock within the motor circuit.

Accordingly, it is the primary object of the present invention to provide a control circuit for hydraulic rams or motors which functions to automatically create a positive lock within a hydraulic motor or ram when it is desired to maintain the plunger or reciprocating member of the ram in a desired stationary position.

It is another object of this invention to provide an improved hydraulic control circuit for hydraulic rams which comprises a control valve operable to introduce fluid under pressure of an associated pump into the pressure area or areas of a hydraulic motor in order to impart movement to the piston or ram member of the motor, and which is operable when occupying a neutral position to by-pass the pump discharge directly to exhaust, and wherein one or more check valves are interposed between the motor ports of the control valve and the pressure area of the motor to establish a positive lock within the motor when the associated control valve occupies its neutral pump by-passing position, whereby to prevent and preclude movement of the reciprocating member of the motor after the same is initially actuated to a desired position.

For a further and more detailed understanding of the present invention and the various additional objects and advantages derived therefrom, reference is made to the following description and the accompanying drawing, wherein:

Fig. 1 is a diagrammatic view of the present improved hydraulic control circuit, in which the control valve and motor are shown in vertical section;

Fig. 2 is a medial longitudinal vertical sectional view taken through a pilot pressure-operated check valve employed in the present control circuit for locking the reciprocating member of a hydraulic motor against slippage; and

Fig. 3 is a horizontal sectional view taken along the line 3—3 of Fig. 2.

Referring now to the drawing, the numeral 5

generally designates a double-acting hydraulic motor or ram which embodies a cylinder 6 in which is carried a piston 7 having a longitudinally extended plunger 8. The side of the piston 7 opposite the plunger 8 is provided with a relatively large flat pressure-responsive face which defines with the side and end walls of the cylinder 6 a piston-advancing pressure area. The side of the piston 7 connected with the plunger 8 defines with the side and end walls of the cylinder 6 a second piston-retracting chamber or area into which fluid may be introduced to retract the plunger with respect to the cylinder. The cylinder 6 is provided at either end with inlet ports 9 for the introduction and release of fluid pressure to and from the separate chambers or pressure areas of the motor.

Fluid pressure for operating the motor 5 and for imparting reciprocatory movement to the plunger 8 is derived from a fluid displacement pump 10 of any suitable type, but which preferably comprises a constant delivery non-reversible type. The pump 10 is provided with an intake or inlet conduit 11 which is in communication with a body of fluid contained in a reservoir 12. The discharge outlet of the pump is connected with a conduit 13 which is connected with the pump inlets 14 of a spool-type control valve 15 by way of the branched conduits 16.

The control valve 15, as shown in detail in Fig. 1, comprises a casing 17 which is formed with an internal chamber 18 and a relatively smaller valve chamber 19. Slidably carried within the valve chamber 19 is a spool-type valve member 20 having end extension shafts 21 extending through the ends of the casing 17 and joined with the armatures of a pair of solenoids 22. Preferably, the rod or shaft 21 of the movable valve member 20 is maintained under spring tension to center the valve member in its full line position as shown in Fig. 1. The valve member 20 may be actuated either to the left or right by selective energization of the solenoids 22.

In its neutral position, the valve member 20 functions to connect the pump ports 14 with a relatively enlarged exhaust chamber 23 formed in the middle of the valve chamber 19. The enlarged chamber or area 23 is provided with an exhaust port 24 which in turn is in communication with the larger chamber 18 of the valve which has communication with a main exhaust port 25 extending through the wall of the casing 17. Upon energization of the left hand solenoid 22 of the control valve, the spool member 20 is shifted leftwardly to connect the left hand pump port 14 with a first motor port or outlet 26, while uncovering a second motor port or outlet 27 to connect the same by way of the right hand end of the chamber 19 with the larger exhaust chamber 18 of the valve.

Simultaneously, the right hand spool of the member 20 covers the right hand pump port 14 to interrupt communication between the latter and the enlarger exhaust area 23. Also, the valve member 20 is provided with an intermediate spool which moves leftwardly into the smaller valve chamber 19 to interrupt communication between the left hand pump port 14 and the exhaust area 23. Upon energization of the right hand solenoid 22, the member 20 is shifted in the opposite direction whereupon fluid under pressure of the pump is directed outwardly through the motor port 27 while connecting the opposite motor port 26 to exhaust. It will be

seen that, in its neutral position, the member 20 provides for the free circulation of fluid displaced by the pump through the control valve by way of the enlarged area 23, the port 24 and the main outlet 25 of the valve which is connected by way of an exhaust conduit 28 with the reservoir 12.

Extending between the motor port 26 of the valve 15 and the plunger advancing area of the motor 5 is a conduit 29, and interposed within the conduit 29 is a pilot-operated check valve 30. This check valve 30 is shown in detail in Figs. 2 and 3 of the drawing, and will be seen to comprise an outer casing 31 in which is formed an inlet port 32 which is connected with the conduit 29 on the control valve side, and an outlet port 33 which communicates with the conduit 29 at its motor-connecting side. The casing 31 is further formed with a plurality of internal interconnected chambers, the uppermost of which slidably receives a movable check valve member 34 which is formed with a tapered lower end 35 for cooperative seating engagement with a valve seat region 36 provided between the uppermost and intermediate chambers or bores of the casing.

The opposite end of the uppermost chamber is closed by a screw threaded plug 37 which limits the movement of the member 34 within the chamber. Interposed between the member 34 and the plug 37 is a light compression spring 38 which lightly urges the member 34 toward its seated position. Thus, the member 34 normally occupies its seated position with respect to the area 36 in which communication between the inlet and outlet ports 32 and 33 is interrupted. The member 34 is further formed at its tapered end with a first pressure-responsive area 39 which is constantly in communication with the inlet port 32, and a second pressure-responsive area 40 which communicates with the outlet 33 by way of a relatively restricted opening 41 formed in the side wall of the member adjacent the outlet 33.

The lowermost chamber of the casing 31 which is substantially larger than the upper and intermediate chambers thereof slidably receives a pressure-responsive piston member 42 having an axially extended plunger rod 43 disposed in longitudinal alignment with the valve member 34. The under face of the piston 42 is in communication with a pilot port 44 which in turn is connected by way of a pilot conduit 45 with the pump discharge conduit 13 between the pump and the control valve 15.

In Fig. 1, it will be seen that the opposite motor port 27 which is connected with the retracting area of the motor 5 by means of a conduit similar to that designated by the numeral 29, may also be provided with an identical pilot-operated check valve 30.

In operation, assuming the piston 7 of the motor 5 to be in a fully retracted position, the plunger 8 of the motor is extended or advanced by shifting the valve member 20 in a leftward direction to connect the discharge of the pump with the conduit 29 leading to the advancing area of the motor. Upon introduction of pressure fluid within the inlet 32 of the check valve 30, the valve member 34 is unseated by pump pressure acting upon the lower pressure-responsive area 39 thereof, and establishes communication between the inlet 32 and the outlet 33 of the check valve, thus allowing of passage of fluid to the advancing area of the motor 5. As the piston 7 of the motor starts to advance, fluid

disposed within the retracting area of the ram is momentarily trapped by the seated valve member 34 of the right hand pilot-operated valve 30 thus creating a build-up in pressure within the pump discharge conduit 13 which, in turn, is transmitted through the pilot conduits 45 to the lower area of the piston member 42 which is immediately elevated to positively unseat the valve members 34 of both valves 30 to permit of circulation of pressure fluid to and from the separate areas of the motor 5.

When the plunger 8 of the motor 5 has been advanced to a desired position, the control valve 15 is neutralized and fluid from the pump is freely by-passed back to the reservoir 12. At this time, the separate valve members 34 of the check valves 30 close, thus interrupting the flow of fluid from both of the areas of the motor 5 in a direction toward the control valve 15. Thus, work-resistance forces transmitted to the plunger 8 of the motor are absorbed thereby due to the positive lock created on both sides of the piston 7 by fluid trapped between the separate pressure areas of the motor and the check valves 30. It will here be seen that any tendency of the motor to slip or creep under the resistance of a load will be positively prevented without depending upon the spool members of the associated control valve 15. When it is desired to retract the plunger 8 of the motor, the valve member 20 of the control valve 15 is shifted rightwardly by energization of the right hand solenoid 22 whereupon pressure fluid from the pump 18 is directed through the right hand motor port 27 of the control valve through the right hand check valve 30 and into the retracting area of the motor. When the piston 7 meets resistance to retracting movement, the pressure in line 13 immediately builds up to a point at which the piston members 42 of the check valves are elevated to unseat the associated valve members 34 to permit of passage of fluid to and from the motor.

It will be understood that only one of the pilot-operated check valves 30 need be employed when it is desired that the plunger 8 of the hydraulic motor be held against load resistance in one direction only, that is to say, when it is desired to prevent creeping of the piston 7 in a backward direction after initial extension. In this event, it is only necessary to employ the pilot-operated check valve 30 within the line or conduit leading to the advancing pressure area of the motor.

In the example shown in Fig. 1, it will be understood that the two check valves 30 employed in each conduit connecting the control valve with the separate areas of the motor function to prevent the possibility of creeping or slippage of the piston in either direction after extension or retraction. It will also be understood that the present improved control system may be used in connection with a single-acting hydraulic ram having a single pressure-responsive area in which it is desired to positively lock fluid to prevent accidental slippage of the ram after the same is actuated to a desired position of extension.

In view of the foregoing, it will be seen that the present invention provides a highly efficient control circuit for employment in connection with hydraulic motors of the type used to actuate an associated clamping or grappling mechanism to its load-engaging position, positive provision being made within the circuit to prevent slipping or retraction of the plunger 8 of the motor after initially extended to its desired position.

While a single preferred embodiment of the present hydraulic circuit has been disclosed in detail, it will be manifest that various modifications as to constructional details may be restored to without departing from the spirit of the invention or the scope of the following claim.

I claim:

In a hydraulic control circuit; a hydraulic ram having a ram-advancing pressure area and a ram-retracting pressure area; a distributing valve having a pair of outlet ports connected, respectively, with the ram-advancing and ram-detracting pressure areas of said ram, an exhaust port and a pressure inlet, and operable selectively to connect the pressure inlet with either of the outlet ports while connecting the opposite outlet port with the exhaust port or to connect the pressure inlet with the exhaust port thereof; a pump connected to circulate pressure fluid to the pressure inlet of said distributing valve; a check valve connected between one of the outlet ports of said distributing valve and the associated pressure area of said ram and having a movable valve member therein normally arranged to interrupt communication between the last-named outlet port of said distributing valve and the associated pressure area of said ram, but being movable in response to the flow of pressure fluid in a direction from said last-named outlet port toward the associated pressure area of said ram to provide free communication therebetween; and fluid-pressure-actuated means engageable with the movable valve member of said check valve and connected directly with the discharge of said pump in bypassing relation to said distributing valve and responsive to a given high pressure within the discharge of said pump for moving the valve member of said check valve to an open position independently of the flow of pressure fluid from said last-named outlet port of said distributing valve toward the associated pressure area of said ram.
